CLAIM

The ornamental design for a combined tree spade and driver, as shown and described.

DESCRIPTION

FIG. 1 is a front and left side environmental perspective view of a combined tree spade and driver showing my new design;

FIG. 2 is a front elevational view thereof;

FIG. 3 is a left side elevational view thereof, the right side elevational view being a mirror image;

FIG. 4 is a rear elevational view thereof;

FIG. 5 is a top plan view thereof; and,

FIG. 6 is a bottom plan view thereof.

The portion of FIG. 1 shown in broken lines represents a user of the claimed design, and forms no part of the claimed design.

FIG. 1

FIG. 2

FIG. 3

FIG. 4

FIG. 5

FIG. 6
